UNITED STATES PATENT OFFICE.

WILLIAM E. KEINE, OF STAMFORD, CONNECTICUT, ASSIGNOR TO ALLIS-CHALMERS MANUFACTURING COMPANY, OF MILWAUKEE, WISCONSIN, A CORPORATION OF DELAWARE.

CRUSHER.

Application filed May 17, 1926. Serial No. 109,464.

This invention relates in general to improvements in the art of crushing, and relates more specifically to improvements in the construction and operation of gyratory crushers or the like.

An object of the invention is to provide an improved gyratory crusher or the like, which is simple in construction, efficient in operation, and which is especially adapted for operation at relatively high speed.

A clear conception of an embodiment of the invention and of the operation of crushers constructed in accordance therewith, may be had by referring to the drawing accompanying and forming a part of this specification in which the various parts are designated by suitable reference characters.

The single figure of the drawing is a central vertical section through an improved high speed gyratory crusher.

The gyratory crusher specifically illustrated comprises generally a stationary main frame 4 providing a support for an annular concave 3, and a gyratable head 2 located within the frame 4 and cooperating with the concave 3 to form an annular downwardly converging crushing chamber 13. The main frame 4 is mounted upon either a flexibly supported or rigidly retained base plate 20 having a final discharge passage 19 therein communicating with the lower discharge opening 18 of the crushing chamber 13. The base plate 20 provides a support for a central bearing member 23 which may be formed integral with or separable from either the frame 4 or the plate 20. An upright shaft 8 is rigidly attached to the bearing member 23 by means of an end taper and a locking bolt 24, the shaft 8 being embraced by a renewable wearing bushing 7 which is secured to the shaft 8 by a locking element 22 and a nut coaxing with the upper extremity of the shaft 8. The upper portion of the frame 4 provides a support for a spider 12 above the inlet opening 17 leading to the crushing chamber 13, and the spider 12 has a central bore which provides a guide bearing 21 surrounding but spaced from the upper ends of the stationary bushing 7 and shaft 8. An eccentric 5 which rests upon a thrust bearing 16 associated with the bearing member 23 has a medial eccentric portion embracing the bushing 7 within the head 2, and has a con-

centric upper portion filling the space between the guide bearing 21 and the upper portion of the bushing 7. A supporting element 6 rests upon a thrust bearing 15 associated with the bearing member 23 and has an upwardly extending sleeve portion which embraces the eccentric portion of the eccentric 5 and which is splined to the interior of the head 2. The head 2 is supported upon jack screws 14 which react against the supporting element 6, these jack screws 14 providing means for vertically adjusting the head 2 relative to the concaves 3 and within the crushing chamber 13. The upper extremity of the eccentric 5 is detachably secured to a drive shaft 11 which is direct connected to a propelling motor 9 by means of a coupling 10. The motor 9 is supported upon an auxiliary frame mounted upon the spider 12 and is located some distance above the inlet opening 17 leading to the crusher.

During normal operation of the machine, the motor 9 is being operated to rapidly rotate the eccentric 5, thus imparting a gyratory motion to the head 2. The material to be reduced is admitted to the crushing chamber 13 between the arms of the spider 12 and through the inlet opening 17 and is gradually reduced as it advances by gravity through the crushing chamber 13. The reduced material is eventually delivered through the discharge opening 18 and is conducted from the crusher through the final discharge passage 19.

If it is desired to vary the fineness of the discharged product, the jack screws 14 may be manipulated to either raise or lower the head 2 within the concave 3, the spline connecting the head 2 with the element 6 permitting such vertical adjustment. The thrust bearings 15, 16 provided for the element 6 and eccentric 5 respectively, upon the bearing member 23, may be effectively lubricated by placing lubricant within the cup formed at the upper extremity of the member 23. The eccentric 5 may be freely removed from within the crusher by removing the spider 12 and withdrawing the eccentric upwardly through the head supporting element 6, whereupon the bushing 7 may be conveniently replaced if necessary. After the spider 12 and the eccentric 5 have been removed, the head 2 and the supporting ele-

ment 6 are freely vertically removable through the concave 3.

The mounting of the motor 9 above the crusher prevents ingress of dirt to the windings, and permits convenient access to the motor at all times. The guide bearing 21 cooperating with the upper end of the stationary shaft 8 cooperating with the rigid lower attachment thereof, provides a rigid support for the eccentric throughout the entire length thereof, and the operation of the crusher at high speed enormously increases the capacity thereof.

It should be understood that it is not desired to limit the invention to the exact details of construction and operation herein shown and described, for various modifications within the scope of the claims may occur to persons skilled in the art.

20 It is claimed and desired to secure by Letters Patent:

1. In combination, a concave, a head co-operating with said concave to form a crushing chamber, a stationary support extending upwardly into said head, an eccentric between said support and said head, and a motor coaxial with said support and direct connected to the upper end of said eccentric for rotating the same to gyrate said head.

2. In combination, a concave, a head co-operating with said concave to form a crushing chamber, a spider above said chamber, a stationary support extending upwardly through said head and into said spider, an eccentric embracing said support and having concentric and eccentric portions within said spider and said head respectively, and means above said spider for rotating said eccentric to gyrate said head.

3. In combination, a concave, a head co-operating with said concave to form a crushing chamber, a movable support supported from below and extending upwardly into said head, a stationary support extending upwardly through said movable support, an eccentric extending downwardly between said stationary and said movable supports, and means for rotating said eccentric from above.

4. In combination, a concave, a head co-operating with said concave to form a crushing chamber, a movable support supported from below and extending upwardly into said head, means for adjusting said head within said concave and relatively to support, a stationary support extending upwardly through said movable support, an eccentric extending downwardly between said stationary and said movable supports, and means associated with the upper end

of said eccentric for rotating the same to gyrate said head.

5. In combination, a concave, a head co-operating with said concave to form a crushing chamber, a spider above said chamber, a movable support below and extending upwardly into said head, a stationary support extending upwardly through said movable support and into said spider, an eccentric embracing said stationary support and having a concentric surface engaging said spider and an eccentric surface engaging said movable support, and means above said spider for rotating said eccentric to gyrate said head.

6. In combination, a concave, a head co-operating with said concave to form a crushing chamber, a spider above said chamber, a movable support below and extending upwardly into said head, means for adjusting said head relatively to said support, a stationary shaft extending upwardly through said support and into said spider, a renewable bushing embracing said shaft within said support and said spider, an eccentric embracing said bushing and said support within said spider, and means above said spider for rotating said eccentric to gyrate said head through said support.

7. In combination, a stationary concave, a gyratable head cooperating with said concave to form a crushing chamber, a bearing member disposed below said chamber, a movable support for said head resting upon said member, an eccentric coacting with said support and resting upon said member, said eccentric extending upwardly beyond said support and said head, and means above said chamber for rotating said eccentric to gyrate said head through said support.

8. In combination, a stationary concave, a gyratable head cooperating with said concave to form a crushing chamber, a bearing member located below said crushing chamber, a stationary support extending upwardly from said bearing member into said head, a movable support resting upon said bearing member and extending upwardly into said head around said stationary support, an eccentric resting upon said bearing member and coacting with said stationary and movable supports within said head, said eccentric extending upwardly beyond said support and said head, and means above said chamber for rotating said eccentric to gyrate said head through said movable support.

100 In testimony whereof, the signature of the inventor is affixed hereto.

WILLIAM E. KEINE.
